US00D413825S

United States Patent [19]

Storsved

[11] Patent Number: Des. 413,825

[45] Date of Patent: ** Sep. 14, 1999

[54] **RESPIRATORY AIR FLOW MEASURING DEVICE**

[75] Inventor: **Mark S. Storsved**, Menomonee Falls, Wis.

[73] Assignee: **CardioPulmonary Technologies, Inc.**, Pewaukee, Wis.

[**] Term: **14 Years**

[21] Appl. No.: **29/093,533**

[22] Filed: **Sep. 14, 1998**

[51] LOC (6) Cl. **10-04**

[52] U.S. Cl. **D10/96**; D24/129

[58] Field of Search D10/96; D24/129; 73/861.52, 861.53, 861.65, 207; 600/532; 128/716, 205.53, 725

U.S. application No. 09/172,486, Storsved, filed Oct. 14, 1998.

Primary Examiner—Antoine Duval Davis
Attorney, Agent, or Firm—Nilles & Nilles, S.C.

[57] CLAIM

The ornamental design for a respiratory air flow measuring device, as shown and described.

DESCRIPTION

FIG. 1 is a top view of a respiratory air flow measuring device showing my new design.

FIG. 2 is a front view of the respiratory air flow measuring device of my new design, said front showing the internal geometry of the device.

FIG. 3 is a side view of the respiratory air flow measuring device.

FIG. 4 is a rear view of the respiratory air flow measuring device.

FIG. 5 is a bottom view (opposite FIG. 1) of the respiratory air flow measuring device; and,

FIG. 6 is a side view (opposite FIG. 3) of the respiratory air flow measuring device.

1 Claim, 1 Drawing Sheet

FIG. 1

FIG. 2

FIG. 3

FIG. 4

FIG. 5

FIG. 6
